US0D1112256S

(12) **United States Design Patent** (10) **Patent No.:** **US D1,112,256 S**
(45) **Date of Patent:** **** Feb. 10, 2026**

(54) **DISPLAY SCREEN OR PORTION THEREOF WITH GRAPHICAL USER INTERFACE**

(71) Applicant: **Otsuka Medical Devices Co., Ltd.**,
Tokyo (JP)

(72) Inventors: **Kristen J. Easterday**, Mountain View,
CA (US); **Charles Richard Lewis, Jr.**,
Carmel Valley, CA (US)

(73) Assignee: **Otsuka Medical Devices Co., Ltd.**,
Tokyo (JP)

(**) Term: **15 Years**

(21) Appl. No.: **29/875,880**

(22) Filed: **May 11, 2023**

(51) LOC (15) Cl. **14-04**

(52) U.S. Cl.

USPC **D14/485**

(58) **Field of Classification Search**

USPC **D14/485-495**

(57) **CLAIM**

The ornamental design for a display screen or portion thereof with graphical user interface, as shown and described.

DESCRIPTION

FIG. 1 is a front view of a first embodiment of a display screen or portion thereof with graphical user interface according to the present design; and,
FIG. 2 is a front view of a second embodiment thereof. The broken line perimeter in each of FIGS. 1 and 2 shows a display screen or portion thereof and forms no part of the claimed design.

The remaining broken lines form no part of the claimed design.

1 Claim, 2 Drawing Sheets
